US00D748215S

(12) **United States Design Patent**
Parsons et al.

(10) **Patent No.:** US D748,215 S
(45) **Date of Patent:** ** Jan. 26, 2016

(54) **GOLF CLUB HEAD**(71) Applicant: **PARSONS XTREME GOLF, LLC**,
Scottsdale, AZ (US)(72) Inventors: **Robert R. Parsons**, Scottsdale, AZ
(US); **Bradley D. Schweigert**, Anthem,
AZ (US); **Michael R. Nicolette**,
Scottsdale, AZ (US)(73) Assignee: **PARSONS XTREME GOLF, LLC**,
Scottsdale, AZ (US)(**) Term: **14 Years**(21) Appl. No.: **29/511,483**(22) Filed: **Dec. 11, 2014****Related U.S. Application Data**(62) Division of application No. 29/501,012, filed on Aug.
29, 2014, now Pat. No. Des. 722,351.(51) **LOC (10) Cl.** ..... 21-02(52) **U.S. Cl.**USPC ..... **D21/759**(58) **Field of Classification Search**USPC D21/736-746, 759

Primary Examiner — Mitchell Siegel(57) **CLAIM**The ornamental design for a golf club head, as shown and
described.**DESCRIPTION**

FIG. 1 is a top perspective view of a golf club head;
FIG. 2 is a bottom perspective view of the golf club head of
FIG. 1;
FIG. 3 is a front elevational view of the golf club head of FIG.
1;
FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a right side view of the golf club head of FIG. 1; and,
FIG. 8 is a left side view of the golf club head of FIG. 1.
The broken line showing is included for the purpose of illus-
trating and forms no part of the claimed design.
